UNITED STATES PATENT OFFICE.

ROBERT P. GARSED, OF NORRISTOWN, PENNSYLVANIA.

ANNUNCIATOR APPARATUS.

SPECIFICATION forming part of Letters Patent No. 453,314, dated June 2, 1891.

Application filed January 24, 1891. Serial No. 378,924. (No model.)

To all whom it may concern:

Be it known that I, ROBERT P. GARSED, of the borough of Norristown, county of Montgomery, and State of Pennsylvania, have invented a new and useful Improvement in Annunciator Apparatus, of which the following is a specification, reference being had to the accompanying drawings to more clearly illustrate the device.

10 The invention relates as well to improvements on my patents, No. 428,810, May 27, 1890, and No. 441,150, November 25, 1890, and has for its object simplicity of mechanism as well as utilization for elevator operation.

15 It relates, also, to certain novel features, as substantially set forth.

Figure 1 is a rear view of the device, partly sectional. Fig. 2 is a sectional side view.

20 Fig. 3 is a perspective view of a gong-hammer bracket. Fig. 4 is a perspective view of a gong-supporting plate. Fig. 5 is a perspective view of a gong-hammer. Fig. 6 represents an elevator-shaft with an elevator, annunciator, and connected mechanism.

25 Fig. 7 is a perspective view of a reciprocating cable-bracket, the socket Z of which, it will be seen, may be placed at either end of spindle H to receive the cable D of the elevator. Fig. 8

30 represents the cable-bracket apart. Fig. 9 is a side view of an annunciator-case, and shows the means of fastening its sides by the hooks U. Fig. 10 is the bottom case-bracket, the holes T of which receive a hook u on either

35 side; and Fig. 11 is a modification of the spring M shown in Fig. 2.

Referring to the drawings, A is an elevator-shaft, and B an elevator adapted to ascend and descend therein.

40 C is an annunciator, and may be either electric or pneumatic, with indicating mechanism placed in any convenient part of the apparatus.

D is an annunciator-cable, and in an ordinary way is attached to annunciator C at one end and at the other by means of reciprocating bracket E to the wall of shaft A, the rear plate E' supporting plate E by means of button F interlocking with it, as will be under-

50 stood.

G is a spiral spring, and while surrounding

spindle H collapses or distends as the weight of cable changes in the ascension and descention of the elevator. The pivotal movement of bracket E allows of the easy adjustment of cable D when in operation, and prevents a too abrupt bending of it at a part apt to affect the transmission of its motor or cause its wear, whether air or electricity be used as such motor. The rotary movement also which 55 spindle H is capable of contributes in a measure to ease said cable in its motions. The weight of cable being felt more at the elevator when said elevator is at its height and at the bracket E when the elevator is at its 60 lowest, the utility of the reciprocating bracket E will be seen, and its being placed both at the elevator and the wall of shaft may be done with advantage.

I is a gong and when in place is upon gong- 70 supporting plate J.

K is the gong-hammer, having lugs K'.

L is a gong-hammer bracket with ears L' for pivoting said gong-hammer.

M is a spring fastened at its lower end to 75 the lifting-rod N, and serves to raise the hammer K in the operation of the device, which is as follows:

The motor, preferably air, being forced from any point to which attention is desired 80 in the line of shaft A in the ordinary way to the annunciator C, through the cable D and inflating-bellows O, causes the lifting-rod N to rise through the medium of its arm P, with the result that spring M, bearing upon the 85 under side of hammer-rod K, raises the same to a height in its pivotal movement that it disengages itself and falls, striking the gong I. The lugs K', bearing upon ears L' of the gong-hammer bracket prevent a continuous bearing 90 of the hammer-head upon the gong, which tends to deaden sound, it being understood that there is enough spring in the length of the hammer-rod from its lugs to its head to allow of its striking and disengaging the gong 95 I. Upon the lowering of rod N, which may be due to gravity, the spring M yields inwardly and allows the parts to assume their normal position, when the device is again ready for operation. The bottom case-bracket 100 shown in Fig. 10, with its downwardly-projecting rear parts, holds as well the annunciator

in a desired place as well as by its ends, affording means for locking the sides of said annunciator.

The button F of the bracket E is preferably made with a smaller body than its head, and when inserted in the corresponding opening on plate E' the said narrow body within the narrow part of such opening is prevented from disengagement by its head. As in long-distance-annunciator operation simplicity of mechanism is very desirable, and a preventive to the disorders arising from great weight of cable and also from its constant use, the advantages of my apparatus will be apparent. The device shown in Fig. 11 shows a pivoted catch, which with its bottom part weighted, as will be seen, acts similar to spring M when used in lieu of it in the operation of the device.

It is meant in my specification and claims to cover and protect any novel combination of elements in their application to bells or annunciators or electric-light wires or other conductors, as especially set forth, without respect to the mere title of my invention, as I take bells to be the equivalent of annunciators and any flexible conductor to be the equivalent of those I set forth.

Having thus described my invention, what I claim as new, and desire to secure by Letters Patent, is—

1. The combination, in an annunciator apparatus, of an elevator, an annunciator, a motor-transmitting cable, and a reciprocating bracket adapted to support and yield to the motions of said cable, substantially as and for the purposes set forth.

2. In an annunciator apparatus, the combination of an annunciator having a gong I, and an actuating lifting-rod carrying a spring M, the hammer-rod K, having lugs K', the supporting-bracket L, with ears L', the said spring M adapted to raise as well as disengage the hammer-rod in the operation of the device, substantially as and for the purposes set forth.

3. In an annunciator apparatus, the combi-

nation of the gong I and an actuating lifting-rod carrying a spring M, the hammer-rod K, the supporting-bracket L, the said spring M adapted to raise as well as disengage the hammer-rod, and the bottom case-bracket with ends extending beyond the sides of the annunciator and adapted with hooks U to fasten said sides and having downwardly-projecting rear parts to support the annunciator in a desired position, substantially as and for the purposes set forth.

4. In combination, an elevator-shaft A, with elevator B adapted to move within such shaft, cable D, fastened to said elevator and shaft and supported by a bracket with pivotal button E, and a socket Z for attachment of said cable, whereby upon the rise or fall of said elevator the movement of said bracket relieves the strain upon said cable, substantially as and for the purposes set forth.

5. In combination, an elevator-shaft A, with elevator B adapted to move within such shaft, an attached cable D, fastened to said elevator and shaft and supported by a bracket having a movable spindle H, with a socket Z for attachment of said cable, said spindle holding a spring G, which, receiving the weight of cable D, collapses or distends in the movement of the elevator, substantially as and for the purposes set forth.

6. The combination, in an annunciator apparatus, of an annunciator having an operative gong supported thereon, an actuating lifting-rod N, having an arm P and an engaging bellows O, said annunciator having sides carrying hooks U and a bottom case-bracket with ends extending beyond the sides of the annunciator and with downwardly-projecting rear parts, which is adapted both to fasten the sides of and hold the annunciator in position, and operative means, substantially as and for the purposes set forth.

R. P. GARSED.
